Application August 30, 1945, Serial No. 613,612

3 Claims. (Cl. 178—44)

1

This invention relates generally to the transmission of radio frequency energy. More particularly it relates to means for preventing changes in characteristic impedance arising from the use of dielectric supports for the inner conductor in coaxial lines.

In the construction of coaxial transmission lines it is necessary to provide supports spaced along the line to maintain the position of the inner conductor in the center of the outer conductor. If there is any deviation from the proper position, the line will not have a fixed, known, calculable characteristic impedance. Indeed, over a long line the deviation may be so great, that the conductors come close enough together to causing arcing over or they may even touch causing a direct short circuit.

Since transmission lines, carrying any appreciable amount of power are subject to vibration, the use of supports for the inner conductor becomes necessary even if the inner conductor is of sufficient inherent strength to support its own weight under static conditions.

Several methods for supporting inner conductors of concentric lines have been in use in the past of which three are so generally used that they may be considered as the only ones of practical importance.

The first of these methods is to use a continuous solid dielectric which completely fills the space between the conductors throughout the length of the line. While this gives complete support to the inner conductor, it has several serious disadvantages. The transmission of energy along the line is delayed to an extent that may be undesirable when a solid dielectric is used instead of air. The use of a continuous solid dielectric support creates a problem when it is necessary to connect the inner conductor to some other type of conductor because of the necessity of connecting a solid dielectric insulated conductor to an air insulated conductor with the resulting abrupt change in characteristic impedance.

A second method is to support the inner conductor at intervals along its length by one-quarter wavelength coaxial stubs which may be manufactured as an integral portion of the line. The outstanding disadvantage of this type of support is that the coaxial stub must be designed for operation at a predetermined frequency, and, if it is desired to operate the line for any frequency other than that one, the efficiency drops off very rapidly as departure from the designed frequency increases. The result is that for practical use such lines are limited to operation over a narrow band of frequencies. Further, for relatively low

operating frequencies, the length of the coaxial stub becomes inordinately great.

The third method in common use is to use circular dielectric discs fitting snugly in the outer conductor and having a central hole fitting snugly over the inner conductor. These discs, commonly referred to in the art as beads, are spaced along the line and held in position by cementing or other suitable means. The disadvantage of this type of a line is that it does not have uniform characteristic impedance throughout its length. The portions of such a line between the beads where the only dielectric is air have a surge impedance which differs from the impedance at the small sections where the beads are located, since the impedance is determined in part by the dielectric constant of the material between the conductors. A modification of this type of line is to fill the entire length of the line with beads. This is, in effect, the same as the use of a solid dielectric and has all the disadvantages of that type of line. In addition, when the line is flexed, trouble is encountered by reason of the small wedge shaped areas between beads at the bent portions.

It is an object of the present invention to provide a coaxial transmission line in which the center conductor is rigidly and accurately supported in the center of the outer conductor by means which permit broad frequency band operation and which will not change the characteristic impedance from point to point along the line.

It is a further object of this invention to permit the line to retain air as its dielectric over the principal portion of its length and to permit the design of a transmission line having any desired proportion of air insulated length.

It is also an object of this invention to devise a supported coaxial line which will permit easy and quick assembly closely following standard coaxial line construction.

Generally, this invention comprises a coaxial transmission line with dielectric centering supports in the form of discs which just fit inside the outer conductor and which have central holes just large enough to permit the inner conductor to be threaded through them and with conductive spacers between each dielectric support. These spacers may be sleeves fitting over the center conductor thus increasing its diameter or may be liners that just fit within the outer conductor thus decreasing its inner diameter. The result of both types is to decrease the characteristic impedance of the spaces between the supports. By choice of proper thickness of these spacers this

2

characteristic impedance may be made of the same value as that where the supports are located.

Other objects, features, and advantages of this invention will suggest themselves to those skilled in the art and will become apparent from the following description of the invention taken in connection with the accompanying drawings in which:

Fig. 1 is a longitudinal cross-section of one embodiment of the invention;

Fig. 2 is a cross-section on line 2—2 of Fig. 1;

Fig. 3 is a longitudinal cross-section of a second embodiment of the invention; and

Fig. 4 is a cross-section on line 4—4 of Fig. 3.

Referring to the embodiment represented in Figs. 1 and 2, the transmission line comprises outer conductor 10 and inner conductor 11. Inner conductor 11 is supported and spaced from outer conductor 10 by insulating beads 12 which are of a circumference to fit snugly within outer conductor 10 and have central holes 13 just large enough to fit over inner conductor 11. Discs 12 are spaced along the line at any desired distance. Metallic spacer sleeves 14 are made to have an inner diameter to fit over inner conductor 11 and a length to reach from one insulating bead 12 to the next.

The outer diameter of sleeves 14 is chosen so that the characteristic impedance at the portions of the line where they occur is the same as the characteristic impedance at the portions where beads 12 occur. Since the effect of putting sleeves 14 over inner conductor 11 is to increase the diameter of that conductor, this may be determined as follows:

The formula for the characteristic impedance of a coaxial line is

$$Z = 138 \log \frac{b}{a} \cdot \frac{1}{\sqrt{K}}$$

where Z is the characteristic impedance, a is the outer diameter of the inner conductor, b is the inner diameter of the outer conductor, and K is the dielectric constant of the material separating the conductors, K for air is unity.

If the diameter, c , of the inner conductor increased by placing the sleeve over it, is such that the characteristic impedance of the line is the same over its whole length, then the following relationship exists:

$$138 \log \frac{b}{c} = Z = 138 \log \frac{b}{a} \cdot \frac{1}{\sqrt{K}}$$

Solving for c ,

$$c = a \sqrt{K}$$

In the embodiment shown in Figs. 3 and 4 instead of fitting conductive sleeves around inner conductor 11, a similar result is obtained by fitting conductive liner sections 15 inside of outer conductor 10. The effect of this is to reduce the inner diameter of outer conductor 10 and, again, the thickness of liners 15 are chosen so that the characteristic impedance of the portions of the line where the liners occur is the same as the portions where insulating beads 12 occur. In this case

$$138 \log \frac{d}{a} = Z = 138 \log \frac{b}{a} \cdot \frac{1}{\sqrt{K}}$$

where the symbols represent the same factors as

before and d represents the inner diameter of liners 15. Solving for d ,

$$d = \frac{b}{\sqrt{K}}$$

The sleeve 14 and the bead 12 at the right hand extremities of Fig. 1 are shown displaced from their normal position in order to show the simple method by which these elements may be slipped over the inner conductor to construct the line. One liner section 15 and one bead 12 are similarly shown in Fig. 3.

It is obvious that connection can be made to a transmission line employing the present invention without the removal of dielectric insulation. This is accomplished by making the connection at a point along the line where either a sleeve 14 or, in the alternate embodiment, a liner 15 is placed. The advantage of such a connection is that discontinuity caused by cleaning a portion of the center conductor of a line employing continuous dielectric throughout its length, is avoided.

Sections of line employing the principles of this invention can easily be joined by any appropriate mechanical means which preserve the inner diameter of the outer conductor and the outer diameter of the inner conductor in the region of the connection.

It will be obvious to those skilled in the art that any suitable dielectric material may be used for supports 12 and any appropriate conducting material for sleeves 14 or liners 15. In order to reduce contact resistance, it is recommended that, where possible, the conductive material used for these parts be the same as that used for the conductors of the line. Further, the geometric shape of the coaxial line can be varied from that having a circular cross-section so long as the basic principles of this invention are followed.

It will be seen that a coaxial line constructed in accordance with the teachings of the present invention will maintain accurate and rigid centering of the inner conductor, will operate over a very wide band of radio frequencies, and will have a uniform value of characteristic impedance from one end to the other.

While there has been here described what is at present considered to be the preferred embodiment of this invention, it will be obvious to those skilled in the art that various changes and modifications may be made therein without departing from the scope of the invention.

What is claimed is:

1. In a coaxial transmission line having an inner conductor concentric with an outer conductor, dielectric support means disposed between said inner and outer conductors at spaced intervals along said inner conductors, said dielectric support means serving to maintain said inner conductor in concentric relationship with said outer conductor, the impedance of said line at each of said dielectric support means differing from that of the unsupported remainder of said line, and a plurality of conductive section means disposed between said dielectric support means and slidably in contact with one of said conductors, said section means being concentric with said conductors, each of said conductive section means having a diameter such that the impedance of said line at all points between said dielectric support means is equal to the impedance of said line at said dielectric support means, resulting in a coaxial line having a uni-

form characteristic impedance despite the presence of said dielectric support means.

2. In a coaxial transmission line having an inner conductor concentric with an outer conductor, said conductors having given uniform diameters, dielectric support means disposed between said inner and outer conductors at spaced intervals along said inner conductor, said dielectric support means serving to maintain said inner conductor in concentric relationship with said outer conductor, the impedance of said line at each of said dielectric support means differing from that of the unsupported remainder of said line, and a plurality of conductive sleeve means disposed between said dielectric support means and slidably in contact with the inner one of said conductors, said sleeve means being concentric with said inner conductor, each of said conductive sleeve means having an outer diameter such that the electrically effective outer diameter of said inner conductor, between said dielectric support means, is made equal to the original outer diameter of said inner conductor multiplied by a factor equal to the square root of the dielectric constant of said dielectric support means, the impedance of said line at all points between said dielectric support means then being equal to the impedance of said line at said dielectric support means, resulting in a coaxial line having a uniform characteristic impedance despite the presence of said dielectric support means.

3. In a coaxial transmission line having an inner conductor concentric with an outer conductor, said conductors having given uniform diameters, dielectric support means disposed be-

tween said inner and outer conductors at spaced intervals along said inner conductor, said dielectric support means serving to maintain said inner conductor in concentric relationship with said outer conductor, the impedance of said line at each of said dielectric support means differing from that of the unsupported remainder of said line, and a plurality of conductive liner means disposed between said dielectric support means and slidably in contact with the outer one of said conductors, said liner means being concentric with said outer conductor, each of said conductive liner means having an inner diameter such that the electrically effective inner diameter of said outer conductor, between said dielectric support means, is made equal to the original inner diameter of said outer conductor multiplied by a factor equal to the reciprocal of the square root of the dielectric constant of said dielectric support means, the impedance of said line at all points between said dielectric support means then being equal to the impedance of said line at said dielectric support means, resulting in a coaxial line having a uniform characteristic impedance despite the presence of said dielectric support means.
